US00D764491S

(12) **United States Design Patent**
Green et al.

(10) **Patent No.:** **US D764,491 S**
(45) **Date of Patent:** **** Aug. 23, 2016**

(54) **DISPLAY SCREEN OF AN ENGINE
CONTROL SYSTEM WITH A GRAPHICAL
USER INTERFACE**

(71) Applicants: **Jason Green**, Davie, FL (US); **Kerry Hackney**, Miami, FL (US); **Chert Nompone**, Sachse, TX (US)

(72) Inventors: **Jason Green**, Davie, FL (US); **Kerry Hackney**, Miami, FL (US); **Chert Nompone**, Sachse, TX (US)

(**) Term: **14 Years**

(21) Appl. No.: **29/506,874**

(22) Filed: **Oct. 21, 2014**

(57) **CLAIM**

The ornamental design for a display screen of an engine control system with a graphical user interface, as shown and described.

DESCRIPTION

The FIGURE is a front view illustrating our design for a display screen of an engine control system with a graphical user interface.

The broken lines in the FIGURE show portions of the display screen of an engine control system with a graphical user interface that form no part of the claimed design.
